STRAIGHT SEAM GUIDE ATTACHMENT
Abe Brenner, 255 W. 23rd St., New York, N.Y.
Filed July 1, 1963, Ser. No. 292,023
6 Claims. (Cl. 112—153)

This invention relates to a guide for use in sewing a straight seam and more particularly to a straight seam guide attachment for use on a sewing machine.

Sewing machine operators often experience difficulty in sewing a straight seam along a continuous length of fabric. This is true even when the operator is skilled and a greater problem with unskilled operators. Often it happens that even the skilled operator may begin the sewing of a seam of a given or desired width, and then gradually, after traversing and sewing a length of two fabrics, ends up with an uneven seam or a seam of a different width. In the use of high speed sewing machines, the problem is magnified and any variation from a straight seam being sewn tends to increase or magnify the irregularity in the complete length of the seam. Also because sewing machine operators often work on the same fabric to produce many like garments, it is necessary that each of the garments have the same straight size or width seams. Reliance is placed upon sight alone for accuracy. In practice, this has been found to be insufficient. Unless the operator is provided with an accurate straight seam guide that will aid in retaining the fabrics in position and limit them in their movement beneath the sewing needle to a desired size, it is impossible to assure that all seams on the same fabric will be straight and of the same width or that the width of any one seam will be straight throughout its length.

Accordingly, an object of the invention is to provide a guide attachment for use during the sewing of a seam on a plurality of fabrics. In carrying forth the purposes of this invention, an object is to provide a straight seam guide attachment that is extremely simple in construction, one that requires but a few moving parts and, therefore, is unusually easy to operate by one who is fully lacking in mechanical skill or ability.

Another object of the invention is to provide a straight seam guide that is capable of being attached to the bed of a sewing machine without interfering with the operator and because it is not required to be affixed to any moving part or mechanism of the sewing machine, it permits the machine to function normally and unhampered.

Further objects and features of the invention reside in the ability to attach the straight seam guide to the bed of a sewing machine in a position remote from that of the sewing needle whereby the straight seam guide retains the fabrics in a sewing position to guide the same during their movement beneath the sewing needle while constantly limiting the free edges of the fabrics, as desired by the operator, to assure an even, straight seam throughout their lengths.

Other and further objects of this invention reside in the structures and arrangements hereinafter more fully described with reference to the accompanying drawing in which:

FIG. 1 is an exploded perspective view of a straight seam guide attachment constructed according to the teaching of the invention.

FIG. 2 is a partial perspective view of the guide attachment assembled in an operation condition.

FIG. 3 is a top view of a modified guide attachment, and

FIG. 4 is a cross section taken along lines 4—4 of FIG. 3.

Referring now to FIGS. 1 and 2 of the drawing, the straight seam guide attachment thereshown is generally identified by the numeral 10. It comprises a base support

2

member 12 that has an under or bottom surface 14 adapted to rest on the bed or top surface 16 (FIG. 2) of a sewing machine. The details of the sewing machine are not fully disclosed since the same form no part of the present invention. However, for the purposes of explanation, the sewing needle 18 and a portion of the presser foot 20 of the sewing machine are illustrated in FIG. 2.

The base support 12 is adapted to slide or be adjustable along and relative to the bed 16 of the sewing machine. 10 It is formed with a pair of laterally spaced upturned legs 22 along its opposite sides. Hence, the base support 12 is substantially U-shaped with the side legs 22 forming the sides of the U shape. The base support member 12 may be of any desired length and includes a longitudinal opening 24 that extends for a portion of the length thereof. 15 As shown in FIGS. 1 and 2, the opening 24 is defined as a slot. However, the length of the opening is not limiting upon the scope of the invention and may be of any desired size. Located forward of the opening 24 is a 20 threaded opening 26.

Positioned on the base support member 12 is a seam guide member 28. The seam guide member 28 is formed as a plate that is provided with a longitudinal extending opening 30 defined therein and extending from the rear 25 end thereof for a substantial portion of the length. The forward end of the seam guide 28 has a down-turned finger 32 formed thereon. The height of the finger 32 is equal to and can be slightly less than the thickness of the base support 12. The width of the seam guide member 30 28 is such that it fits between the laterally spaced upturned legs 22 of the base support member 12 to engage the facing adjacent inner surfaces of such legs and thereby 35 its sliding movement relative to the base support is guided by the cooperating engaged legs. Because the finger 32 is proportioned with respect to the thickness of the base support 12 as described, its edge moves smoothly along for adjustment relative to the face of the bed 16 of the sewing machine.

Positioned on and movable relative to the seam guide 40 member 28 and for adjustment and movement relative to the base support member 12 is a fabric cover plate member 34. The cover plate 34 is provided with a longitudinally extending opening 36. The width of the plate 34 is substantially equal to the lateral spacing between the upturned legs 22 of the base support 12 so when the cover plate 34 slides and moves relative to the seam guide 28, its movement is guided by the legs 22 with which its 45 respective sides cooperatively engage. The cover plate 34 is provided with a plurality of graduations 38 which function 50 as a measuring scale to indicate the relative position of adjustment of the downturned guide finger 32 located therebeneath. The position of the guide finger 32 can be sighted with the graduations on the cover plate 34 through the longitudinal opening 36.

The straight seam guide attachment 10 is assembled and the parts thereof secured together by the passage of a thumb screw or securing means 40 downward through the aligned longitudinal openings 36 and 30 until it engages with the mating threads of the opening 26 in the base support 12. The assembly is adapted to be attached to the bed 16 of a sewing machine and to be secured to the same by passing the threaded end of a second thumb screw or securing means 42 downward through the aligned longitudinal openings 36, 30 and 24. The threaded end of the thumb screw 42 is adapted to be threadedly engaged in a mating threaded opening 44 provided in the bed 16 of the sewing machine.

When the thumb screws 40 and 42 are loosened, the three members 12, 28 and 34 are permitted movement relative to each other and to the bed 16 of the sewing machine. The cover plate 34 is moved so its forward

edge 46 abuts or engages with the adjacent side of the sewing machine presser foot 20. The seam guide member 28 is then moved relative to the cover plate 34 until its downturned finger 32 is positioned at the desired graduation 38 beneath the cover plate 34 to locate the position of the seam and provide the size of the seam inward from the edges of the fabrics desired to be sewn by the sewing needle 18. The longitudinal opening 24 in the base support member 12 permits the same to be adjusted relative to the bed 16 of the sewing machine to accommodate large as well as narrow width seams. After the members are adjusted into their desired positions, the thumb screw 40 is tightened down to lock all the members together. Thereafter, the thumb screw 42 is threaded down tightly into the sewing machine bed 16 to lock the parts of the straight seam guide attachment directly to the machine.

In FIG. 2, the fabrics to be sewn together are shown at 48 and 50. Their free edges 52 are initially positioned against the downturned finger 32 of the seam guide 28 so that the face of the finger 32 engaged by the edges 52 acts as a guide face and is positioned in the direction of movement of the fabrics to provide a smooth surface against which the edges 52 move and are guided. The cover plate 34 overlays the fabric bodies 48 and 50 so as the fabrics are sewn, they must move thereunder. As the fabrics move under the cover plate, they are forced to assume substantially the same flat condition as the sewing presser foot 20 causes the fabrics to assume as the needle 18 stitches them together at the seam 53. Because the fabrics 48 and 50 are flattened and guided by the cover plate 34 during their movement, the edges 52 are constantly moved into guiding cooperative engagement with the adjacent guide face of the finger 32. Hence, the finger 32 constantly limits the widthwise size of the seam 53 to keep it straight and even while the cover plate 34 retains the edges 52 against the guiding-limiting finger 32.

The straight seam guide attachment 10 limits the size of the seam and guides the fabrics during their movement while the seam is being sewn. The guide attachment thus assures that the seam size or location will be the same, even and straight, for the continuous length of fabrics. Until the members 12, 28 and 34 are readjusted relative to each other, all fabrics guided thereby will have the same straight and equal width seams.

Referring now to FIGS. 3 and 4, the embodiment thereshown is generally identified by the numeral 100. The straight seam guide attachment 100 is substantially like that of the guide attachment 10 previously described. Therefore, for ease of explanation, parts of the guide attachment 100 corresponding to those of the guide attachment 10 will have the same tens digits, but will be numbered in the 100 series. This manner of numerical referencing should obviate redundant or superfluous recitations of previously described structural details and functions.

The base support 112 is provided with a longitudinal opening 124 and has its under surface 114 resting on and for relative adjustment to the bed 16 of the sewing machine. Positioned and guided between the upturned legs 122 of the base support 112 are the seam guide members 128 and the cover plate member 134.

The longitudinal openings in the members 112, 128 and 134 are aligned with each other to permit the passage of a thumb screw 142 therethrough for engagement with a threaded opening 144 defined in the bed 16 of the sewing machine. As noted in the prior described embodiment 10, when the thumb screw 142 is unthreaded in its opening 144, the members 134, 128 and 112 are capable of being moved and adjusted relative to each other and to the bed 16 of the sewing machine. However, when the thumb screw 142 is tightened in its mating thread 144, the whole guide attachment 100 is locked together whereby the members thereof are locked from

relative movement and from movement relative to the sewing machine bed 16.

In the prior embodiment 10, the numbers 12, 28 and 34 were moved relative to each other by manual adjustment until such time that each of such members assumed their desired positions. In the present embodiment, the base support member 112 is provided with a rotatable pinion 154 that is adapted to engage with a set of rack-shaped engaging means or teeth 156 defined along a wall of the longitudinal opening 136 of the cover plate member 134. The pinion 154 is adapted to be rotated by finger pressure and includes a knurled knob 158 that has a stem thereof extending downward through the longitudinal opening 130 of the guide member 128 and is secured to the base support 112 as at 160.

A further adjustment member 158a is mounted for rotation at 160a on the base support member 112 and includes engaging means in the form of a rotatable pinion 154a that is adapted to cooperate with engaging means 156a in the form of rack teeth defined along one wall of the longitudinal opening 130 of the guide member 128. Both the guide member 128 and the cover plate member 134 have their longitudinal openings 136 and 130 in alignment with the longitudinal opening 124 of the base support member 112. In the present embodiment, however, the longitudinal opening 136 of the cover plate member 134 extends fully to the rear edge in the same manner as does the longitudinal opening 130 of the guide member 128.

Those skilled in the art will readily recognize that when the thumb screw 142 is unthreaded slightly from its mating opening 144, the three members of the guide attachment 100 are permitted relative finite adjustment and longitudinal movement. This relative longitudinal adjustment and movement may be accomplished simply by rotating the thumb screws 158 and 158a to adjust the cover plate member 134 and the guide member 128 each independently of and relative to the other, as well as to the base support 112. Thus, the members of the straight seam guide attachment 100 are always connected together and may be secured as an attachment unit by the thumb screw 142 to the bed 16 of a sewing machine. The members may be locked together from relative movement when the thumb screw 142 is tightened into its mating opening 144. The widthwise size of the fabric seam will be limited by the relative position of the face of the downturned guide finger 132. The fabrics will constantly be moved or urged into engagement with this guiding and limiting finger as they move beneath the cover plate 134 in the same manner as described with respect to embodiment 10.

While there have been shown and described and pointed out the fundamental novel features of the invention as applied to several preferred embodiments thereof, it will be understood that various omissions and substitutions and changes in the form and details of the devices illustrated and in their operations may be made by those skilled in the art, without departing from the spirit of the invention. It is the intention, therefore, to be limited only as indicated by the scope of the claims appended hereto.

I claim:

1. A straight-seam guide for attachment to the bed of a sewing machine comprising first, second and third members, said second member being movable relative to the other members and to the bed of a sewing machine, guide means on said second member to engage an adjacent edge and to guide a plurality of overlying fabrics to be sewn and to limit the location of the seam thereof, guide means on said first member to guide said second member for movement relative thereto, said third member having a flat undersurface covering and flatly overlying and engaging the upper adjacent surface of one of the plurality of fabrics to retain the same flat with its edge in engagement with said guide means, said third member

including means to indicate the location of said guide means and the location of the seam on said fabrics, and means cooperable with said members to lock the same against relative movement and against movement relative to the bed of a sewing machine, the height of said guide means being substantially equal to that of the thickness of the overlying fabrics when the same are retained flat by said third member.

2. A straight seam guide attachment as in claim 1, engaging means on said first and second members, said engaging means including means operable to cause said members to move relative to each other.

3. A straight seam guide attachment as in claim 1, engaging means on said first and third members, said engaging means including means operable to cause said members to move relative to each other.

4. A straight seam guide attachment as in claim 1, engaging means on said first, second and third members, certain of said engaging means being operable to cause said members to move relative to each other.

5. A straight seam guide attachment as in claim 4, said engaging means being a rack on said second and third members and a rotatable pinion on said first member, said engaging rack and pinion guiding said members during their movement relative to each other.

6. A straight seam guide for attachment to the bed of a sewing machine to guide a plurality of fabrics in overlying relationship during their movement beneath a sewing machine needle comprising first, second and third members, said first member being elongated and U-shaped in cross-section to receive said second and third members between the upstanding legs thereof, said second member being positioned in said U-shaped first member for guided movement between the upstanding legs thereof and on the base thereof, said third member being positioned between the upstanding legs of the U-shaped first member and on said second member, one edge of said third member extending beyond a corresponding edge of said first member, said extending edge of said third member having a flat

undersurface spaced from the bed of the sewing machine, said second member being movable between said first and third members and having a straight guide edge movable in the direction of and away from said one edge of said third member and directly beneath the flat undersurface thereof, the height of said guide edge extending for substantially the space between the flat undersurface of said third member and the bed of the sewing machine, the space between said flat undersurface and the bed of the sewing machine corresponding substantially to the thickness of the plurality of overlying fabrics to engage the uppermost one of the fabrics to flatten the same to the shape of the flat undersurface of said third member while an edge of each one of the plurality of overlying fabrics engages said straight guide edge, means engaging between said first and second members to move said second member in the direction of and away from said one edge of said third member, and means cooperable with said members to attach the same to the bed of a sewing machine.
